COMBINED ADHESIVE MAGNETIC-ELECTRIC
TAPE AND POWER SOURCE THEREFOR

St. Barth Alaska, 3811 S. Scoville Ave.,
Berwyn, Ill. 60402

Filed May 19, 1969, Ser. No. 17,218

Term of patent 14 years

Int. Cl. D13—03

U.S. Cl. D26—1

FIG. 1

FIG. 2

FIG. 1 is a perspective view of a combined adhesive magnetic-electric tape and power source therefor showing my new design, the tape being broken away to indicate indeterminate length.

FIG. 2 is a cross-section taken on line 2—2 of FIG. 1 showing the novel design.

The magnetic bulbs are shown in broken lines in FIGS. 1 and 2 for illustrative purposes only.

I claim:

The ornamental design for a combined adhesive magnetic-electric tape and power source therefor, as shown and described.
